DEVICE FOR PURIFYING THE BREATHING
AIR IN A VAPOR BATH FOR THERAPEUTI-
CAL USE

Zensei Fujita, Yotsuya-ku, Tokyo, Japan

Application February 24, 1937, Serial No. 127,567
In Japan February 24, 1936

1 Claim. (Cl. 128—191)

This invention relates to a device for purifying the breathing air in a vapor bath for therapeutical use, and comprises a casing, means for introducing heating medium vapor into said casing, means for supplying mist of aqueous solution of calcium hydroxide or barium hydroxide into said casing, and means for supplying oxygen or ozone gas into said casing, for the purpose of continuously transforming carbon dioxide gas produced in the casing into calcium carbonate or barium carbonate and for supplementing oxygen therein.

The object of the invention is to provide a vapor bath for therapeutical use which can be borne for a sufficiently long time, from 2 to 6 hours, to secure a desired therapeutic effect by maintaining an elevated temperature of the body, without producing any injurious or dangerous consequence caused by breathing trouble.

In the accompanying drawing in which one embodiment of the invention is shown by way of example:—

Fig. 1 is a side elevation of the therapeutical vapor bath according to this invention,

Fig. 2 is a plan view, and
Fig. 3 is a cross sectional view thereof.

Referring to the drawing, a base 1 is supported in a slightly inclined position by four legs. To said base 1 is mounted a casing 2 provided with a hinged door 3 and a window 4 having a shield of transparent material. Within said casing 2 above the base 1 is mounted a bed 5. Beneath said bed 5, there are provided pipes *a*, *a* one being supplied with vapor of a heating medium, and the other being supplied with aqueous solution of calcium hydroxide or barium hydroxide. The latter pipe *a*, as shown in Fig. 3 of the drawing, is provided with means, which may assume the form of a plurality of spray nozzles or openings or any other suitable and conventional expedient, whereby mist of the solution of calcium hydroxide or barium hydroxide is produced and discharged within the casing. In the head portion of the casing, there is arranged a pipe *b* for supplying oxygen or ozone gas into the casing. The discharge end of the said pipe *b* is arranged in such position that the oxygen gas is discharged above the face of the patient. For example, the vapor of the heating medium is discharged in the casing in the amount of from 10 to 50 litres per minute; the mist of aqueous solution of calcium hydroxide or barium hydroxide is discharged in the amount of from 300 to 600 c. c. per minute; and oxygen or ozone gas is discharged in the amount of from 300 to 600 c. c. per minute.

In the heretofore practiced vapor bath treatment, on account of the increasing amount of carbon dioxide gas produced in the casing by the respiration of the patient, the patient often suffers from heart-trouble and anaemia, and sometimes death of the patient occurs. According to this invention, not only it is possible to vary conveniently the length of the time of treatment, but also it is possible to avoid such danger encountered in the heretofore practiced vapor bath treatment as described. By experiments, it has been found that during the bath treatment the breathing air in the casing is changed as follows:—By breathing, an adult ordinarily consumes oxygen of about 250 to 300 c. c. per minute, and discharges carbon dioxide gas of about 200 to 300 c. c. per minute. A patient under treatment, who has an elevated temperature, consumes oxygen of 500 to 600 c. c. per minute and discharges carbon dioxide gas of 400 to 600 c. c. per minute.

Now, the amount of oxygen consumption and the amount of carbon dioxide discharge taken in time is diagrammatically shown as follows:—

(1) Oxygen consumption

(2) Carbon dioxide gas

The above-mentioned examples (1) and (2) have been both taken from the breathing of a

patient having temperature of the body of 40°-42°.

When the carbon dioxide content in the breathing air increases, the patient suffers from a heart-trouble and anaemia on account of poor oxygen content, and often death of the patient occurs. Presence of 2% of carbon dioxide in the breathing air will produce injurious effect, and over 2% of carbon dioxide brings blush, evomitition, and unconsciousness, and with from 6% to 7% of carbon dioxide the patient will be suffocated to death.

From the above-mentioned diagram (2), it will be seen that at 30 minutes after starting the treatment the carbon dioxide content becomes about 3%, and after 60 minutes it becomes about 6%. Thus, on continuous treatment for about one hour the patient would be suffocated to death. In view of the above, the heretofore employed therapeutical vapor bath could not be borne for more than 20 minutes. Consequently, it was not possible to secure the desired degree of therapeutic effect. While it is well known that for obtaining good therapeutic effect the vapor bath should be borne for a greater length of time (from 2 to 6 hours), maintaining the elevated temperature of the body, heretofore it has not been possible practically to effect the continuous treatment for so long time, since the breathing air in the casing is soon changed into a dangerous condition.

According to this invention, calcium hydroxide

or barium hydroxide introduced into the bath is combined with carbon dioxide produced in the bath, and is transformed into the harmless substance as follows:—

or

Thus, it will be seen that carbon dioxide produced in the bath is removed by producing calcium carbonate or barium carbonate, and that at the same time oxygen is supplied. Consequently, according to the invention, the vapor bath can be borne for a desired longer time at will, and it is possible to attain a desired therapeutic effect, without causing any dangerous consequence.

What I claim is:—

A device for purifying the breathing air in a vapor bath for therapeutical use, comprising a casing, means for introducing heating medium vapor into said casing, means for supplying mist of aqueous solution of a member of the group consisting of calcium hydroxide and barium hydroxide into said casing, and means for supplying oxygen or ozone gas into said casing, for the purpose of continuously transforming carbon dioxide gas produced in the casing into calcium carbonate or barium carbonate and for supplementing oxygen.
